UNITED STATES PATENT OFFICE.

WILLIAM BELLMAR, OF ASTORIA, NEW YORK, ASSIGNOR TO ASTORIA SILK WORKS, OF LONG ISLAND CITY, NEW YORK, A CORPORATION OF NEW YORK.

PLUSH-LOOM-CUTTER STOP.

Application filed May 25, 1923. Serial No. 641,474.

To all whom it may concern:

Be it known that I, WILLIAM BELLMAR, a citizen of the United States, and a resident of the city of New York, Astoria, 5 borough of Queens, in the county of Queens and State of New York, have invented a new and Improved Plush-Loom-Cutter Stop, of which the following is a full, clear, and exact description.

10 This invention relates to stop motions for looms and particularly for plush looms, and has for an object to provide an improved construction wherein the cutter used in the loom may automatically stop the loom when 15 the operating mechanism therefor fails to properly function.

Another object of the invention is to provide an improved connection between the cutter of a plush loom and the regular stop 20 mechanism thereof so that when the mechanism for moving the cutter fails to operate, the machine will be automatically stopped by its regular stop mechanism.

A still further object more specifically is 25 to provide an improved arrangement for stopping a plush loom when the operating rope of the cutter breaks, the arrangement being such as to require no change in the stop motion mechanism of the loom or any 30 change in the construction of the rope operating mechanism of the cutter.

In the accompanying drawings—

Figure 1 is a fragmentary front view of 35 a plush loom showing a cutter mechanism and a stop motion mechanism embodying the invention associated therewith;

Fig. 2 is a fragmentary side view of the 40 loom shown in Fig. 1, with the connecting stop motion mechanism embodying the invention shown applied thereto;

Fig. 3 is a fragmentary diagrammatic view illustrating how the stop motion mechanism of the machine operates;

Fig. 4 is a fragmentary rear view of part 45 of the stop mechanism shown in Fig. 2.

Referring to the accompanying drawings by numeral, 1 indicates the frame of a plush loom, which frame supports the various mechanisms necessary to complete the loom.

50 As the particular mechanism of the loom forms no part of the present invention, the same has been omitted principally from the drawings and will not be described.

In connection with the loom, a cutter 2 is

used to cut the pile during the operation of 55 the machine. This cutter may be of any type and is operated or moved back and forth by a cable 3, which passes over suitable guiding pulleys 4 and 5, as well as over a number of other pulleys 6 supported 60 in any suitable manner by the frame 1, whereby the cable is permitted a free back-and-forth movement and also whereby proper mechanism may be connected therewith for causing a proper back-and-forth 65 movement thereof. This cable, the pulleys, and the cutter 2, are of a well-known construction. Heretofore this arrangement has been used, and when the cable 3 breaks, the operator must stop the loom in order to 70 prevent injury to the fabric being woven.

In order to automatically stop the loom when the cutter cord or cable 3 breaks, a special mechanism has been provided, which is associated with the usual stop motion 75 mechanism of the loom and is connected up in such a way as to function without disturbing the stopping of the loom by the automatic means in the usual manner.

As indicated in Fig. 1, the pulley wheel 7 80 rests against the cable 3 and preferably presses the same outwardly by reason of its weight. This pulley is pivotally mounted in any suitable manner upon a bar 8 pivotally supported as at 9 on a fixed stationary 85 bracket 10 carried in any suitable manner by the frame 1. The bar 8 is provided with a pin 11 which projects through a slot or elongated aperture 12 formed in the end of a crank arm 13, which crank arm is bent 90 at 14 or at this point formed integral with a rearwardly-extending shaft 15. The shaft 15 is carried by any desired number of supporting brackets 16, and at the rear end is provided with an upstanding arm 17 bent 95 at 18 to form a bar 19 which supports a U-shaped connector 20, the bar 19 being connected to the connector 20 in any desired manner. The connector 20 is one of a number of similar connectors used in the system 100 shown in Fig. 3, (except that it is connected with bar 19) which system is a well-known system now commonly used on plush looms.

This system of stop-motion consists essentially in providing insulated contact 105 plates 21 and 22, said contact plates being straddled by the respective connectors 20, and said connectors being supported in any

suitable manner by the threads of the machine except the one connected to the bar 19 so that when any thread breaks, that particular connector will drop under the action 5 of gravity and assume the position shown in Fig. 3. This will connect the plates 21 and 22 so that current will flow through these two plates from the source 23 and also through the respective wires 24, 25 and 26, 10 so as to energize the electromagnet 27. When the electromagnet 27 is energized, it will move the armature 28 so that the extension 29 will move away from the contact post 30. This breaks the circuit of the motor 31, which motor is connected up for driving the loom. The particular connector 20 secured to the bar or rod 19 is swung back and forth by said bar instead of being dropped by gravity, and said bar through 25 the shaft 15 and associated parts, is moved under the action of the arm 8. This arm is swung downwardly to the dotted line position shown in Fig. 1, by the pulley 7 acting under gravity when the cord or cable 3 breaks. As the pulley 7 is pivotally mounted on the supporting bar or arm 8, it will freely rotate with a back-and-forth movement as the cable 3 reciprocates. By reason 30 of this construction and arrangement, the cutter 2 may freely reciprocate to perform its usual function without molesting the stop mechanism, which stop mechanism is caused to function when the cable 3 breaks and permits the pulley to swing downwardly so that shaft 15 will be rocked and the connector secured to bar 19 moved down-

wardly to the position shown in Figure 3.

What I claim is:—

1. The combination with a plush loom provided with a cutting mechanism formed 40 with a cable or ligament and a stop motion for the loom provided with a number of connectors for closing the electrical circuit used in stopping the loom, of a member normally supported by said ligament, and a 45 plurality of means connected with said member and operated and with one of said connectors thereby when said ligament permits said member to move downwardly, said downward movement resulting in a sufficient 50 operation for said members to move one of said connectors into operative position.

2. The combination with a loom provided with a stop motion mechanism including a substantially U-shaped connector adapted 55 to be in operative position when lowered and in inoperative position when raised, said loom also being provided with a cutting mechanism constructed with a cable, of means actuated when said cable breaks for 60 moving one of said connectors to an operated position for stopping said loom, said means including a pivotally mounted arm, a wheel carried by said arm and normally resting against said cable, a rock shaft actuated by said arm when the same moves from a given position, and means actuated by said rock shaft for moving one of the connectors to an operative position whereby the loom will be stopped when said cable is broken. 65

WILLIAM BELLMAR.
